UNITED STATES PATENT OFFICE.

JAMES CHARLES ORR AND CHARLES TWEEDIE CLUFF, OF WINNIPEG, MANITOBA, CANADA, ASSIGNORS, BY MESNE ASSIGNMENTS, OF ONE-THIRD TO JAMES CHARLES ORR, ONE-THIRD TO CHARLES TWEEDIE CLUFF, AND ONE-THIRD TO MICHAEL B. MILL, ALL OF WINNIPEG, CANADA.

COAL BURNER.

Application filed January 8, 1923. Serial No. 611,421.

To all whom it may concern:

Be it known that we, JAMES CHARLES ORR and CHARLES TWEEDIE CLUFF, both of the city of Winnipeg, in the Province of Manitoba, Canada, have invented certain new and useful Improvements in Coal Burners, of which the following is the specification.

The invention relates to improvements in coal burners and an object of the invention is to provide a device for insertion in the fire pot of a furnace and which is particularly constructed for use in the burning of soft coal in the furnace, the device being constructed to supply air for combustion purposes and to separate the fire pot into two fire compartments, such latter permitting of the alternate firing of the coal in opposite sides of the fire pot.

20 A further object is to construct the appliance such that it can be readily inserted in the furnace through the fire door and such that it is entirely supported by the grate bars.

25 A further object is to construct the appliance in a simple, durable and practical manner and such that it can be produced and installed at a comparatively small cost.

With the above more important objects in view the invention consists essentially in the arrangement and construction of parts hereinafter more particularly described and later pointed out in the appended claims, reference being had to the accompanying drawing in which:

Fig. 1 is a perspective view of the device.

Fig. 2 is a face view of the double winged divider.

40 Fig. 3 is a horizontal sectional view through the hollow post, the section passing through the side channels.

45 Fig. 4 is a vertical sectional view centrally through the appliance as it appears in the fire pot, the divider being shown in side elevation.

In the drawing like characters of reference indicate corresponding parts in the several figures.

50 In the burning of soft coal considerable care has to be exercised in order to get the best results from the same and also to prevent explosions in the furnace. We have

devised the burner herein described for insertion in the customary fire pot 1 of the furnace, the burner being located centrally of the furnace and having the base thereof resting on the grate bars 2. The burner presents a hollow body or post 3 having a centrally disposed neck 4 which flares out 60 and terminates at the bottom in an enlarged base 5 and has the upper end terminating in a hollow ball or sphere 6. The ball at the top is provided with a plurality of openings 7 which permit of air coming up 65 through the grate bars and out the openings into the combustion chamber. The post has the base thereof wholly supported by the grate bars and it is located centrally of the fire pot.

At diametrically opposite sides the neck is supplied at the exterior with opposing spaced pairs of vertical flanges 8 and 9 cast integrally therewith and forming vertical channels or guides 10 and 11, the lower ends 75 of the guides being closed by the flaring portion of the base.

Associated with the post we provide a divisional member which passes in a direction centrally across the fire pot and which acts to divide the same into two firing compartments. This divisional member in the present instance is in the form of a single casting presenting two similar side wings 12 and 13 connected by a top arched 85 and suitably reinforced strap 14. The strap is adapted to seat on the top of the ball or sphere and the inner edges of the wings are designed to slidably enter the guides or channels 10 and 11 of the post. By forming 90 this divisional member in this way one can first insert the post through the fire door and locate it properly on the grate bars, then he can insert the divisional member and place it in position on the post and 95 in this connection it is advisable to have the divisional member passing in a direction from the front to the back of the furnace as this makes it a very easy matter to fire the coal used to either side of the 100 fire pot.

When the divider is in place within the furnace the ball is above the coal level and the lower edges of the wings are above the grate bars, whilst the ends thereof are entirely clear of the inner side of the fire pot.

When this device is in use a low fire is primarily built on the grate bars in the fire pot, then the soft coal is thrown into one side of the fire pot up to, say, the height of the 5 upper end of the neck of the burner. The heat of the fuel bed distills out the combustible gas which passes into the combustion space over the fire and is mixed with sufficient air, provided through the openings 7, 10 to provide a combustible mixture which ignites. This prevents any possibility of explosion.

Gradually the coal in the compartment will come to a nice even glow and when it 15 has burnt down one throws fresh coal into the other side of the fire pot. The gases of this fresh coal are distilled out by the heat of the fire in the other compartment and, mixing with the air, become ignited in the 20 combustion chamber.

The operation of alternately firing in opposite sides of the fire pot is continued each time new coal is placed in the furnace.

We might also mention that the burner 25 is made of cast iron and has fairly thick walls so that it becomes very hot and accordingly assists in distilling out the gas and also in heating, to a high temperature, the air supplied through the grate bars and 30 out the openings 7 to the combustion chamber.

What we claim as our invention is:

1. A coal burner for insertion in the fire pot of a furnace, comprising a hollow post 35 having the base thereof resting on the furnace grate bars and having the upper end thereof closed and provided with a plurality of air outlet openings communicating with the combustion chamber, and a removable divisional member carried entirely by the 40 upper end of the post and extending across the fire pot in an elevated position above the grate bars and dividing the fire pot into two firing compartments.

2. A coal burner for insertion in the fire pot of a furnace, comprising a hollow post positioned centrally of the fire pot and having the lower end thereof resting on the 45 grate bars and the upper end communicating with the combustion chamber of the fur-

nace, and a divisional member removably supported by the upper end of the post and anchored against rotation therearound, said divisional member being elevated clear of the grate bars and passing transversely of 55 the fire pot and dividing the same into two firing compartments.

3. A coal burner for insertion in the fire pot of a furnace, comprising a hollow post positioned centrally of the fire pot and having the base thereof resting on the grate bars and the upper end thereof terminating in a 60 perforated ball, an elevated divisional member crossing the fire pot and dividing the same into two firing compartments and having the lower edge thereof clear of the grate bars, said divisional member being removable and hung from the ball and being prevented from rotation around the post.

4. A coal burner for insertion in the fire 70 pot of a furnace, comprising a hollow post positioned centrally of the fire pot and having the lower end enlarged and resting on the grate bars and the upper end closed and perforated, and diametrically opposed pairs 75 of vertically extending spaced flanges provided on the post and forming vertical guideways at the opposite sides thereof.

5. The combination with a hollow perforated post for insertion within the fire pot of 80 a furnace, said post being provided with diametrically opposing vertically extending guides, of a divisional member insertible within the fire pot and elevated above the 85 grate bars thereof and dividing the same into two firing compartments and in the form of a pair of wings having their inner edges adapted to be received within the guides, the said wings being connected by a strap passing over the upper end of the 90 post and supporting the said divisional member.

Signed at Winnipeg, this 8th day of December, 1922.

JAMES CHARLES ORR.
CHARLES TWEEDIE CLUFF.
